MACHINE FOR MAKING STENCILS

Louis Rogers and Joseph Ettl, Brooklyn, N. Y.,
assignors to Rogers Industries, Inc., New York,
N. Y., a corporation of New York

Application September 10, 1947, Serial No. 773,242

2 Claims. (Cl. 93—1)

1

This invention relates to a machine for automatically making stencils in a single and continuous operation.

The stencil is composed of a blank backing strip having a line of perforations and a stencil sheet which is suitably attached to the backing sheet by adhesive or the like adjacent to the line of perforations.

This invention is particularly directed to an automatic machine having mechanism which is of rotary character and which is very rapid in operation.

An object of this invention is to provide an elongated drying unit having a through passage for coated tissue paper and a plurality of air inlet passages and electric heating elements for the respective passages, and to provide a wire mesh screen above the heating elements to prevent direct contact of the tissue paper with the heating elements.

Another object of this invention is to provide a large capacity suction blower to carry away the components of the coating liquid from the drying unit during the travel of the papers through the drying unit in order to prevent explosion and fire hazards.

Another object of this invention is to produce a machine for making a plurality of rows of stencils simultaneously at a high speed, and without any manual operations from the start to the completion of the finished stencil, the stencil being dried during the passage of the papers through the machine.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a plan view of the automatic stencil making machine.

Figure 2 is a central cross-sectional view of the coating unit and the drying unit, the section being taken as on line 2—2 in Figure 1.

Figure 3 is a central cross-sectional view of the combining unit, the section being taken as on line 3—3 in Figure 1.

Figure 4 is a central cross-sectional view of the cutoff and punch unit, the section being taken as on line 4—4 in Figure 1.

Figure 5 is a side elevation of the automatic stencil making machine.

Figure 6 is a schematic view of the stencil papers showing the steps in the method employed in the manufacture of the stencils.

In the illustrated embodiment of the inven-

2

tion, the numeral 10 indicates a machine for automatically making a two-member paper stencil in a single and continuous operation, comprising a coating unit 11 having a receptacle 12 in which is a suitable coating liquid 13.

The coating unit 11 has a tension roller 14 rotatably mounted at its outer face. A coating roller 15 is rotatably mounted in the receptacle 12 with the lower portion of the roller immersed in the coating liquid 13. A tissue paper supply roll 16 is rotatably supported on a shaft 17 in bearings 18 mounted on a bracket 19 in front of the coating unit 11.

A scraper 20 contacting the roller 15 serves to regulate the thickness of coating. The scraper 20 is mounted in the receptacle 12 preferably above the center line of the coating roller and above the level of the coating liquid.

A coating smoothing bar 21 of square cross-section is mounted in the receptacle 12 in horizontal alignment with the top of the coating roller 15 and with one of its edges in direct contact with the coated surface of the tissue paper.

A belt 22 connected to an electric motor 23 drives a pulley 24 and the coating roller 15 in a direction opposite to the direction of motion of the tissue paper 16'.

A drying unit 25 is positioned in alignment with the coating unit 11 at the discharge end 30 of the coating unit. The drying unit 25 consists of an elongated and suitably insulated chamber 26 comprising a front wall 27 having a narrow opening 28 and a rear wall 29, having a narrow opening 30. The openings 28 and 30 permit the coated tissue paper 16' to pass therethrough while being dried in the chamber 26.

At the rear wall 29 of the drying unit 25 is a rotatably mounted roller 31, the lower edge of which contacts the upper face of the coated tissue paper 16'. At the bottom of the drying chamber 26 are a plurality of transverse strips 32 spaced apart to form openings 33 through which air may enter into the drying chamber. Suitable baffle housings 34 guide the incoming air past elongated heating elements 35 running transversely of the chamber 26. Roller 31 is mounted on shaft 39.

Spaced above the heating elements 35 is a horizontal protective screen 36 which prevents the tissue paper 16' from contacting the heating elements in case of a break in the tissue paper while the machine is in operation.

Positioned in suitably spaced relation above the tissue paper 16' is a plurality of strips 37 spaced apart from each other to form transverse openings 38 through which the air and products of evaporation may be sucked out from the chamber 26.

A suction exhaust fan 40 is mounted on the upper surface of the drying chamber 26 and

communicates with the interior of the chamber to exhaust the air therefrom.

Rearwardly of the drying unit 25 and in alignment with the coating unit and with the drying unit is a combining unit 45 (Figure 3) having brackets 46 at its front face 47 which serve to rotatably support a backing paper supply roll 48. The roll of backing paper is positioned at a level below the guide tension roller 31 in the drying unit 25.

Fixedly mounted in an upright position inside the combining unit 45 is an elongated decurling bar 49. In the combining unit 45 above the bar 49, are two serrated perforating disk knives 50 which are rotatably mounted on a shaft 51 and are spaced apart from each other to produce two parallel rows of perforations 41 lengthwise of the backing sheet 48', that is, a row at each lengthwise side edge of the sheet 48'.

The shaft 51 is rotatably mounted in slide-blocks 52 which are movable in slots 53 in the side walls 54 of the combining unit 45. Plates 55 are secured to the walls 54 in covering relation with the slots 53. Bolts 56 threaded in the plates 55 and contacting the slide blocks 52 serve for moving the shaft 51 and the perforating disk knives 50 against a feed roller 57. The roller 57 is mounted on a shaft 58. The bolt 56 and the slide block mounting of the shaft 51 provides means whereby pressure may be applied to paper 48' passing between the perforating disk knives 50 and the roller 57.

Rotatably mounted in spaced relation from the feed roller 57 is an upper feed roller 59 mounted on a shaft 60, and a lower feed roller 61 mounted on a shaft 62.

Mounted rearwardly of the three feed rollers 57, 59 and 61 are two strip gluing units 65 which are spaced apart crosswise and serve for applying narrow strips of adhesive along the two lengthwise side edges of the backing sheet 48' outside of, adjacent and parallel to the perforations 41 in the backing sheet.

Each strip gluing unit 65 comprises a receptacle 66 which is pivotally mounted on a rod 67, and a narrow roller 68 mounted centrally of the receptacle 65. The roller passes through a close fitting slot in the inclined rear wall of the receptacle and rests on a support roller 57² which is mounted on a shaft 69. A portion of the roller 68 is immersed in glue in the receptacle 66.

Rotatably mounted in the combining unit 45, at the rear of the strip gluing units 65 is a thumb notch die cutting roller 71. The roller 71 is made of a size such that one-half of its circumference is equal to the width of a stencil.

Suitably fixed diametrically opposite, in the roller 71, are two hollow punches 72 of circular cross-section. The roller 71 is mounted in spaced-apart relation from the roller 57³ so that the punches only will contact the roller 57³. Each hollow punch 72 has a sharp circular cutting edge which presses against the solid roller 57³. The roller 57³ is freely rotatably mounted on a rotating shaft 74. The roller 71 is mounted on a shaft 73.

Rotatably mounted at the rear of the thumb die cutting roller 71 is a pair of combining rollers 76, 77. The upper combining roller 76 is mounted on a shaft 80. The shaft 80 is rotatably mounted in guide blocks 52 which are movable in slots 53 in the side walls 54 of the combining unit 45. Plates 55 are secured to the walls 54 in covering relation with the slots 53. Bolts 56 threaded in the plates 55 and contacting the 75

slide blocks 52 serve for moving the shaft 80 so as to bring the roller 76 in forced relation against the roller 77. The roller 77 is mounted on a shaft 81. The bolt 56 and the slide block mounting of the shaft 80 provides means whereby pressure may be applied to the combined papers 16' and 48' passing between rollers 76 and 77.

A cutoff and punch unit 85 is positioned rearwardly of and in alignment with the combining unit 45. The unit 85 comprises an upper slitting disk knife 86 which is rotatably mounted on a shaft 87. The shaft 87 is rotatably mounted in slide blocks 52 which are movable in slots 88 in the side walls 89 of the cutoff and punch unit 85.

Plates 55 are secured to the walls 89 in covering relation with the slots 88. Bolts 56 threaded in the plates 55 and contacting the slide blocks 52 serve for moving the shaft 87 and the upper slitting disk knife 86 against a lower slitting knife 90, mounted on a shaft 91.

The bolt 56 and the slide block mounting of the shaft 87 provides means whereby pressure may be applied to the combined papers 16' and 48' passing between the slitting disk knives 86 and 90. The slitting knives are rotatably mounted at the middle of the combined papers and form two continuous lengths of stencil material 95.

Mounted rearwardly of the slitting disk knives 86 and 90 is a feed roller 96 mounted on a shaft 97. The shaft 97 is rotatably mounted in slide-blocks 52 which are movable in slots 53 in the side walls 89 of the cutoff and punch unit 85.

Plates 98 are secured to the walls 89 in covering relation with the slots 53. Bolts 56 threaded in the plates 98 and contacting the slide blocks 52 serve for moving the shaft 97 and this moves the roller 96 against an intermittent feed roller 100. The slide-blocks for the roller 96 are resiliently supported at their lower ends on springs 101.

The intermittent feed roller 100 is mounted on a shaft 102. The peripheral surface of the roller 100 is made of a size to press against the roller 96 and feed the combined papers.

A portion 103 of the outer surface of the roller 100 is cut away so that only a portion of the said surface will function to feed the combined papers. The roller 100 has slots 104 and bolts 105 for adjusting the roller 100 for timing its feeding action.

Rearwardly of the intermittent feed rollers 96 and 100 is a cutoff and punch press 110 comprising a fixed bed 111 having bearings 112 which slidably support rods 113.

Secured to the upper ends of the rods 113 is a crosshead 114 and a punch carrier 115 having a plurality of punches 116, each preferably having a key-shaped cross-section. The punches are arranged in two parallel rows and coact with receiving apertures 117 in the bed 111 to punch cylinder engaging apertures 118 in the two rows of stencil material 95.

Secured to the rear portion of the crosshead 114 is an upright cutoff blade 119. Secured to the bed 111 is a coacting cutoff blade 120. The blades 119 and 120 serve to cut off finished stencils 125 from the two rows of duplicate stencil material 95.

The actuating means for imparting reciprocating motions to the crosshead 114 and the punches 116 consists of two identical open face disk cams 126 mounted on shafts 127. Rollers 128 at the lower ends of the rods 113 follow the outer surfaces of the cams and move downwardly due to the

weight of the crosshead. Each cam 126 has a portion of its periphery 129 cut away to permit the punches 116 to drop suddenly when the punching action takes place in the stencil paper and the blades 119, 120 cut off the stencils.

Gears 130 are mounted on the shafts 127 and intermesh with a gear 131 which is driven by a pulley 132 from a motor 133. The two gears 130 drive the two cams 126 in timed relation. The punches 116 are timed to work during the inactive period of the intermittent feed rollers 96 and 100.

The finished stencils 125 drop on an endless belt conveyor 125 and are then carried to a receiving platform 136.

As best shown in Figure 5, there is provided a separating space 137 between the combining unit 45 and the cutoff and punch unit 85. This space permits the combined papers 16' and 48' which feed at a continuous rate of speed during the passage through the combining unit 45 to feed intermittently when passing through the cutoff and punch unit 85. This is possible due to the fact that the excess material accumulated during the non-feeding period occasioned during the punching operation can drop to a lower level and the loop increases in length during the non-feeding period.

The wrinkle eliminating roller 63 is mounted on a shaft 64 and is located close to the upper combining roller to press out any wrinkles that may have been formed in the process of treating the tissue paper.

It is to be noted that a belt driven variable speed unit 146 shown in Figure 5, is driven from a pulley 147 on a cam gear shaft 121 and drives a pulley 148 on the lower combining roller shaft 81.

The variable speed unit 146 comprises a constant speed shaft 149 and a variable speed shaft 150.

It is to be noted that the main drive gear 131 drives both cam gears 130 and that an idler gear 140 transmits motion from a cam gear 130 to a gear 141 mounted on the lower intermittent feed roller shaft 102 and that an idler gear 142 transmits motion from the gear 141 to a gear 143 mounted on the lower slitting knife shaft 91. The gear 143 transmits motion to a gear 144 mounted on the shaft 87 of the upper slitting knife 86.

Operation of invention

The tissue paper 16' from the supply roll 16 passes over the tension roller 14, then above the receptacle 12, and in contact with the coating roller 15, then through the openings 28, 30 in the front and rear walls 27, 29 of the drying unit 25, then through the drying unit while in contact with the roller 31 at the rear of the drying unit, then in contact with a guide roller 75 mounted on a shaft 78 on top of the combining unit 45, then over a wrinkle eliminating roller 63 mounted on a shaft 64, and then between the two combining rollers 76, 77.

Simultaneously with the passage of the tissue paper 16', as above described, the backing paper 48' from the supply roll 48 passes below the tissue paper 16', over the decurling bar 49, around the guide roller 61, then between two perforating rollers 59 and the coating roller 57, then between the paper feed knives 57 and 59, above the support roller 57² and beneath the strip gluing roller 68, then between the support roller 57³ and the thumb notch punch roller 71 to punch thumb

notches 99 lengthwise and at the middle of the backing paper, and then between the two combining rollers 76, 77. The combining rollers 76, 77 adhesively combine the two papers 16' and 48' along the glued narrow edge portions 42 of the backing sheet 48'.

The adhesively combined papers then pass through the slitting disk knives 86 and 90 in the cutoff and punch unit 85, shown in Figure 4, 10 where the material is slit longitudinally intermediate the two lengthwise side edges of the tissue paper and through the backing paper to form two continuous lengths of duplicate stencil material 95.

15 The two rows of duplicate stencil material 95 then pass through intermittent feed rollers 96 and 100, which feed the stencil papers intermittently through the combined cutoff and punch press 110 where the material is punched to form 20 cylinder engaging apertures 118 on letter duplicating machines, and where the material is cut to pre-determined stencil length in one operation.

Driving mechanism

25 The shaft 73 (Figure 3) has the roller 71 and a sprocket gear 151 fixed thereto. The shaft 152 (Figure 4) intermediate the cams 130 has a sprocket gear 153 fixed thereto. The sprocket gear 151 is twice the diameter of the sprocket gear 153. A sprocket chain 154 in engagement with the sprocket gears 151 and 153 transmits motion from the shaft 152 to the shaft 73 at a reduced speed to permit a large diameter punch roller 71 containing two punches 72 to punch 35 two stencils in a period of one revolution of the roller 71, the circumference of the roller 71 being twice the width of a stencil.

It is to be noted that a V-belt 159 connected to a pulley 160 on the variable speed shaft 150 drives the pulley 148 on the shaft 81 of the lower combining roller.

A sprocket gear 161 on the shaft 81 drives a sprocket gear 162 on the shaft 69 by means of a sprocket chain 163. A further sprocket gear 164 mounted on the shaft 69 drives a sprocket gear 165 on the shaft 58 by means of a sprocket chain 166. A gear 167 on the shaft 68' is driven by the gear 162. A gear 168 on the shaft 81 drives a gear 169 on the shaft 80. A belt 170 (Figure 4) suitably connects a shaft 171 on the conveyor 135 with the cam shaft 127 for driving the conveyor.

In accordance with the patent statutes we have described and illustrated the preferred embodiment of our invention, but it will be understood that various changes and modifications can be made therein without departing from the spirit of the invention as defined by the appended claims.

We claim:

1. In a machine for automatically making in a continuous operation two rows of two-layer paper stencils respectively glued together solely along a narrow crosswise strip, comprising means for mounting a roll of coated tissue paper, a roll of rotatably mounted backing paper having a width greater than said tissue paper and positioned below said tissue paper, means for punching two parallel rows of perforations lengthwise and adjacent both side edges of said backing paper, means for applying glue in the form of two narrow strips on said backing paper adjacent the perforations, means for punching thumb notches lengthwise and at the middle of said backing paper, a combining unit having pressure feed

7
rollers for continuously feeding said papers in superposed relation to adhesively combine both edge portions of said papers adjacent said perforations, means for slitting said combined material longitudinally and through said thumb notches to form two continuous lengths of equal width two-layer stencil material, means for intermittently feeding said combined papers into a punch and cutoff press for punching key-shaped cylinder engaging apertures in exposed side portions of said backing sheet, said cutoff and punch press and said combining unit being spaced apart from each other to provide space where said combined papers form a variable loop to permit said cutoff and punch press to operate intermittently while said combining unit operates continuously, and means for cutting said rows of combined stencil materials to form two rows of two-layer stencils of predetermined length.

2. In a machine for automatically making in a continuous operation two rows of two-layer paper stencils respectively glued together solely along a narrow crosswise strip, comprising means for mounting a roll of tissue paper, a roll of rotatably mounted backing paper having a width greater than said tissue paper, means for punching two parallel rows of perforations lengthwise and adjacent both side edges of said backing paper, means for applying glue in the form of two narrow strips on said backing paper adjacent the 30 perforations, means for punching thumb notches lengthwise and at the middle of said backing paper, a combining unit having pressure feed rollers for continuously feeding said papers in superposed relation to adhesively combine both 35

8
edge portions of said papers adjacent said perforations, means for slitting said combined material longitudinally and through said thumb notches to form two continuous lengths of equal width two-layer stencil material, means for intermittently feeding said combined papers into a press for punching key-shaped cylinder engaging apertures in exposed side portions of said backing sheet, said press and said combining unit being spaced apart from each other to provide space where said combined papers form a variable loop to permit said press to operate intermittently while said combining unit operates continuously, and means for cutting said rows of combined stencil materials to form two rows of two-layer stencils of predetermined length.
